METHOD OF MAKING HYDROBROMIC ACID

Grayton F. Dressel and Otto C. Ross, Midland, Mich., assignors to The Dow Chemical Company, Midland, Mich., a corporation of Michigan

Application October 30, 1933, Serial No. 695,743

4 Claims. (Cl. 23—156)

This invention relates to methods of making hydrobromic acid wherein hydrogen and bromine are reacted directly with each other.

Various methods have hitherto been used to effect the aforesaid reaction. For instance, bromine vapor and hydrogen may be reacted by mixing the same in approximately combining proportions, and causing them to burn at a suitably elevated temperature. Another method 10 consists in reacting in vapor phase at a lower temperature in the presence of a porous catalyst, such as activated charcoal, silica gel, or the like. There are some practical disadvantages connected with both of these procedures which make them 15 unsatisfactory for a commercial process. In the first mentioned method it has been found practically impossible to produce a water-white hydrobromic acid solution when the reaction product is absorbed in water. This is apparently due 20 to the existence of free bromine in the product, which occurs even when an excess of hydrogen is employed in the reaction and indicates that the reaction does not go entirely to completion, at least not within the time interval during which 25 the gases traverse the combustion zone. Theoretically this condition could be remedied by extending the length of the combustion zone sufficiently, but this has not been found practical in apparatus adapted for commercial operation.

30 In the aforementioned catalytic method it has been found possible to avoid the presence of free bromine in the product, but the rate of reaction is reduced to but a fraction of that of the combustion method, and the output from an apparatus of given size is reduced excessively.

35 We have now devised an improved method for carrying out the reaction whereby a water-white acid solution can be produced continuously at a rate equal to that obtained in the aforesaid 40 combustion method. The improved method constituting our invention is fully set forth in the following description which is to be read with reference to the annexed drawing.

In said drawing:

45 The single figure shows diagrammatically a form of apparatus adapted for carrying out the method of the invention.

Referring to the drawing, a bromine vaporizer and gas mixing chamber 1, made of a metal resistant to bromine, e. g. lead, or of ceramic material, is placed in a temperature regulating water bath in a tank 2. Inlet pipes 3 and 4 serve to introduce bromine and hydrogen, respectively, into vaporizer 1, while a water inlet 5 and 50 overflow pipe 6 is provided to control the water

bath in tank 2. A vertical tube 7 of silica or heat resistant glass leads from the top of vaporizer 1 and connects the latter with a tubular reaction chamber 8, likewise preferably made of heat-resistant glass. Tube 7 terminates at its 5 upper end in a burner tip 9, just below which in the tube is located a small body 10 of granular porous material, e. g. charcoal. A perforated cap 11 of porcelain, carbon or other heat and corrosion resistant material is placed over burner 10 tip 9, but spaced therefrom, being supported on a shoulder in the lower part of reaction chamber 8. Just above the lower end of chamber 8 is an enlarged section 12 into which the burner 9 and cap 11 extend. Through the sides of enlargement 12 are inserted two adjustable ignition electrodes 13, connected with a source of current of suitable voltage.

The upper end of chamber 8 is connected by a U tube 14 with a column 15 which contains a 20 body 16 of granular porous adsorbent material, such as active charcoal, pumice, silica gel, or similar metallic oxide gels. Means is provided for heating the column, for instance an electric resistance element 17. From the bottom of column 15 a tube 18 connects with the base of a scrubber column 19 of usual form filled with a body of packing material, and surrounded by a water jacket. A water inlet 20 and vent 21, are provided at the top of scrubber 19, and a trapped 30 outlet 22 at the bottom, the latter containing a hydrometer well, as shown.

In the operation of the foregoing apparatus a body of liquid bromine is maintained in vaporizer 1, through which hydrogen is bubbled, thereby 35 vaporizing bromine and producing a gaseous mixture of hydrogen and bromine. The temperature of the vaporizer is held by means of the water bath at the proper point in relation to the vapor tension of bromine and rate of flow of hydrogen introduced, so that a gas-vapor mixture is produced in which the volume of bromine is nearly equal to that of hydrogen. In practice at the rate of 40 gas flow required to feed the burner, the temperature of the vaporizer is held between 37° and 42° 45 C., e. g. about 40° C., whereat the mixture contains a small excess, e. g. about 10 per cent by volume, of hydrogen. The bromine-hydrogen mixture passes into burner tube 7, in which 50 thorough intermixing is accomplished by passage through the body of charcoal 10, and emerging from the burner tip 9 is ignited by a spark between electrodes 13. After ignition the reaction maintains itself and continues as long as the proper proportions of bromine and hydrogen are 55

5 maintained. A considerable excess of hydrogen in the mixture will not materially affect the continuance of the reaction, but an excess of bromine is to be avoided, since even a slight excess thereof will extinguish the flame and hence interrupt the reaction. In case the flame should go out for this or any other reason, the gases may be reignited, as in the first place, by means of the spark electrodes. These electrodes are made adjustable, and can be drawn back when not in use. 10 When cap 11 is made of a conducting material such as carbon, the spark can be drawn between the electrodes and the cap.

15 The rate of introduction of hydrogen gas into the vaporizer 1 is regulated so as to maintain the temperature in the combustion zone between about 600° and 850° C. We have found that the perforated cap 11 over the burner tip 9, by becoming heated to incandescence, assists the smooth 20 and even burning of the gases. The reaction gases traverse the chamber 8 in which a considerable cooling takes place by radiation, and pass thence into adsorber column 15 where they are brought into intimate contact with the active charcoal 25 or other adsorbent porous contact material therein. Such charcoal adsorbs unreacted bromine and hydrogen in the gases and holds the gases until they react to form hydrogen bromide. The body of adsorbent material should be heated to an elevated 30 temperature to carry out the reaction of hydrogen and bromine therein. In practice, a temperature between about 150° and 200° C. is suitable, although higher temperatures may be used.

35 The completely reacted gases, containing no free bromine, are conducted into the base of scrubber 19, wherein they are absorbed in water. By suitably regulating the volume of water admitted at inlet 20 in proportion to the volume 40 of hydrogen bromide in the reaction gases an aqueous hydrobromic acid solution of any strength up to complete saturation may be readily obtained. The temperature of the liquid within the scrubbing column may be controlled by 45 passing cooling water through the water jacket. The strength of the effluent acid at outlet 22 may be continuously determined by means of the hydrometer as shown. In ordinary operation a strong solution of approximately 48 per cent HBr 50 content is prepared. From outlet pipe 22 the aqueous acid is conducted away for filling into containers.

55 We have attempted to operate the above described apparatus while dispensing with a charge of adsorbent material in column 15, but have not succeeded in this way in preparing water-white hydrobromic acid. Inasmuch as a water-white acid is required for most commercial purposes, the purity of the product made is of first importance, hence we have found it necessary, in employing 60 the combustion method of reacting bromine and hydrogen, to combine therewith the step of passing the gases through a body of adsorbent material in order to obtain a sufficiently pure product.

65 A particular advantage of our improved method is the relatively high capacity of the apparatus as compared with the prior art method in which the reaction of bromine and hydrogen is carried out 70 entirely within a body of contact material. In our experience with the commercial operation of such last-mentioned method, employing activated charcoal for the contact material, the highest yield of hydrogen bromide, figured as 100 per 75 cent HBr, obtained was approximately 6 pounds

per 24 hours per square inch cross section of the reaction chamber. On the other hand, with the method and apparatus of the present invention, employing a body of active charcoal of the same depth as before, we are enabled to produce from 5 35 to 40 pounds of 100 per cent HBr per 24 hours per square inch cross section of the adsorber, as substantially pure water-white acid solution. Another advantage is that the accidental introduction of excess bromine, or the extinguishment of 10 the flame for any cause, will not result in the carrying forward of unreacted bromine to contaminate the hydrobromic acid solution product. Such excess bromine is adsorbed on and held by the active charcoal or other adsorbent employed, 15 while the hydrogen bromide passes through. Subsequently such adsorbed bromine is converted in situ to hydrogen bromide by reaction with hydrogen, when the presence of a sufficient excess thereof in the reaction gases is re-established. 20 The method, then, is adapted for the uninterrupted production of pure water-white hydrobromic acid solution regardless of irregularities in supplying the proper proportions of hydrogen and bromine to the burner, or other disturbances 25 which interfere with complete reaction of the bromine.

Other modes of applying the principle of our invention may be employed instead of the one explained, change being made as regards the 30 method herein disclosed, provided the step or steps stated by any of the following claims or the equivalent of such stated step or steps be employed.

We therefore particularly point out and distinctly claim as our invention:—

1. The method of making water-white hydrobromic acid solution which comprises passing hydrogen through a body of liquid bromine maintained at a temperature between 37° and 42° C. 40 to form an approximately equimolecular mixture of bromine vapor and hydrogen, burning the mixture, while causing the flame to impinge upon a surface of heat resistant material maintained at incandescence by the heat of the flame, partially cooling the combustion gases, passing the latter through a body of active charcoal maintained at a temperature between about 150° and about 200° C., and absorbing the purified hydrogen bromide gas in water.

2. The method of making water-white hydrobromic acid solution which comprises passing hydrogen through a body of liquid bromine maintained at a temperature between 37° and 42° C. 55 to form an approximately equimolecular mixture of bromine vapor and hydrogen, thoroughly intermixing the vapors and gases by passing through a body of porous granular material, burning the mixture, while causing the flame to impinge upon a surface of heat resistant material maintained at incandescence by the heat of the flame, partially cooling the combustion gases, passing the latter through a body of active charcoal maintained at a temperature between about 150° and about 200° C., and absorbing the purified 60 hydrogen bromide gas in water.

3. The method of making water-white hydrobromic acid solution which comprises passing hydrogen through a body of liquid bromine maintained at a temperature between 37° and 42° C. 70 to form an approximately equimolecular mixture of bromine vapor and hydrogen, thoroughly intermixing the vapors and gases by passing through a body of porous granular material, burning the mixture, while causing the flame to 75

impinge upon a surface of heat resistant material maintained at incandescence by the heat of the flame, regulating the rate of supply of hydrogen so that the temperature in the combustion space is maintained between about 600° and about 850° C., partially cooling the combustion gases, passing the latter through a body of active charcoal maintained at a temperature between about 150° and about 200° C., and absorbing the purified hydrogen bromide gas in water.

4. The method of making water-white hydrobromic acid solution which comprises passing hydrogen through a body of liquid bromine main-

tained at a temperature between 37° and 42° C. to form a mixture of bromine vapor and hydrogen containing a slight excess of hydrogen, burning the mixture, while causing the flame to impinge upon a surface of heat resistance material maintained at incandescence by the heat of the flame, partially cooling the combustion gases, passing the latter through a heated body of adsorbent porous contact material, and absorbing the purified hydrogen bromide gas in water.
